Primary Examiner — Erich G Herbermann*Assistant Examiner* — David Weir(74) *Attorney, Agent, or Firm* — Xia Li; CAIP(57) **CLAIM**

The ornamental design for a pet bath cart, as shown and described.

DESCRIPTION

FIG. 1 is a perspective view of a pet bath cart showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion “9” in FIG. 1; and,

FIG. 10 is an enlarged view of portion “10” in FIG. 1.

The broken lines in the drawings depict portions of the pet bath cart that form no part of the claimed design. The dash-dot-dash broken lines seen in FIGS. 1, 9, and 10 define areas of enlarged detail views. And form no part of the claimed design.

1 Claim, 10 Drawing Sheets(56)
